UNITED STATES PATENT OFFICE

EMIL F. HOLINGER, OF NEW YORK, N. Y., ASSIGNOR TO HUDSON ELECTRICAL HEATING CORPORATION, OF NEW YORK, N. Y., A CORPORATION OF NEW YORK

WATER HEATER

Application filed July 25, 1928. Serial No. 295,134.

This invention relates generally to water heaters for domestic use, but is more particularly designed to produce such a heater adapted for operation by an electrically operated heating member. In essence the invention comprises a water holding tank having an opening in one wall and an apparatus adapted to hold an electrically operated, or equivalent, heating unit and distribute the heat therefrom, which apparatus can be inserted through said opening as a unit and then attached to the tank for closing said opening.

The best form of apparatus at present known to me embodying my invention is illustrated in the accompanying two sheets of drawing in which

Fig. 1 is a vertical central section of the hot water heater, and

Fig. 2 is a horizontal section on line 2—2 of Fig. 1.

Throughout the drawings like reference characters indicate like parts.

1 is a cylindrical boiler shell, 1^a the top or dome sheet therefor welded or otherwise joined to one end thereof and 1^b the inwardly dished bottom head welded to the other end of shell 1. A hole 2 is formed preferably centrally of the heater dome 1^a, and this is surrounded by a welded-on ring 3, to which a cover plate 4 may be held by bolts 5, 5. A tube 6, adapted to contain an electric heating member or other heating member, has one end welded into an opening in plate 4. Tube 6 is closed at its other end by plate 7, preferably welded thereto, and this plate carries a central, projecting pin 8 which engages an opening 10 in the bridge-like member 9, which is welded to the bottom head 1^b. As shown, pin 8 is a short section of tube, as this can be conveniently welded to plate 7.

The nipple 11 serves as the water inlet connection to water tank formed by 1, 1^a, 1^b, and 12 is the nipple for the outlet connection. 45 13 is a nipple for a drain connection and 14 a nipple for a thermostat.

15 is the cylindrical portion of an outer shell adapted to be closed at one end by the bottom plate 15^b, which may be welded there- 50 to, and also at the other end by the top plate

15^a. This casing 15, 15^a, 15^b, surrounds the water containing tank, leaving spaces which may be filled with any convenient non-heat-conducting material to reduce the loss of heat by radiation from the hot water tank. 55 16, 16, are guide lugs fastened to the inner surface of the bottom plate 15^b, and circumferentially arranged thereon, said lugs having exterior convexly curved faces, as shown in Fig. 1.

60 17 is a cylindrical skirt or jacket surrounding heater-holding tube 6 and welded thereto at the upper end, near which point it is provided with openings 18, 18, in its walls. The lower end of this tubular skirt 17 is left 65 open and may be centered with reference to tube 6 by inserting three pins 19 in the annular space between the two tubes. 20 is a third tube surrounding tubular jackets 17 and leaving a small annular space between 70 the two, said tube 20 being welded to tube 17 at either end so as to form a hermetically sealed annular air jacket around it.

In assembling the parts the water tank 1 is set in the jacket shell 15, being accurately 75 centered with reference thereto by the flanges of the tank head 1^b slipping over the inwardly curved guide lugs 16, 16, on the bottom plate 15^a of the outer casing. The various nipples 11, 12, 13, 14, are then inserted 80 and the heater-carrying unit is placed in the tank, the pin 8 engaging the recess 10 in the member 9 to center the same. The space between the walls of the tank and the casing 15 may then be filled with any loose heat insulating material, the jacket cover 15^a is placed in position, and bolts 5, 5, inserted 85 through it and through plate 4 into ring 3 to hold the parts together, and close the opening to water tank 1.

90 While the heater-carrying unit is rigidly fastened only at one end, the pin 8 in the other end and nested in member 9 serves to prevent its vibrating injuriously during transportation and handling of the heater. 95 If anything goes wrong with the heating apparatus, the whole unit can be removed at once by simply taking out bolts 5, 5, and a new one inserted.

99 In operation the water in the annular space

between tube 6 and its tubular skirt 17 is rapidly heated by radiation and conduction from the heater in tube 6 and rises with corresponding rapidity, flowing out through the holes 18. This zone of high heat inside of tube 17 is protected from cooling by direct radiation to the water in the body of the tank by means of the air jacket formed by outer tube 20, as before explained. As a result whenever the heat is turned on there will be promptly produced a body of warm or hot water at the top of tank 1 long before the main body of the water in the middle and lower portion has absorbed any substantial amount of heat. This quickly formed body of hot water can be drawn immediately upon by the user to whom it will be delivered through the discharge nipple 12, and incoming cold water through inlet nipple 11 will largely pass immediately to the lower end of the tube 17 and upward within the same to be immediately heated and delivered at the top of the tank to maintain the supply of hot water there segregated for immediate use. 25 When the user ceases to draw on this supply, and the heater is continued in action, the hot water zone will gradually extend downward and through the body of the tank as the water confined therein moves in closed loop paths 30 down along its center walls and up through the annular passage between tubes 6 and 17.

Various changes could be made in the details of construction above described without departing from the underlying principles 35 of the invention herein intended to be set forth.

Having described my invention, I claim:

1. In a water heater the combination of a water tight tank, a tube arranged centrally 40 and vertically therein having a closed end within said tank and adapted to receive a heat producing element through its other end, a surrounding skirt for said tube welded to said tube at one end and provided with perforations in its walls near said end, whereby it is adapted to form an annular water passage between said tube and skirt, and a sealed air jacket surrounding said skirt comprising a continuous tube of larger diameter welded 45 to said skirt near each end thereof.

2. In a water heater the combination of a water tight tank having an opening in its upper wall and a heater-holding unit comprising a tubular shaped structure closed at 50 one end, open at the other end, and having a flange surrounding said open end fastened to said tank wall around the margin of the opening therein; whereby said heater-holding unit may be readily mounted in, or removed from, said tank interior combined with a projection from the closed end of said heater holding unit and a perforated member carried by the adjacent walls of the tank engaging said projection.

3. In a water heater the combination of a

cylindrical tank having an opening in one head, a tube adapted to be inserted through said opening, said tube being closed at one end and provided at the other with a flange adapted to be fastened to said tank head 70 around said opening, bolts for fastening said flange to said tank head, and a tube of larger diameter surrounding said first mentioned tube, fastened to it near its flanged end and provided with perforations near its said fastening and opening at its other end, together with a third tube of still larger diameter surrounding said second tube and sealed thereto at either end, whereby an annular water 75 circulating passage is formed around said first mentioned tube and a heat insulating jacket formed about said second tube.

4. In a water heater the combination of a cylindrical tank having an opening in one head, a tube inserted through said opening, 80 said tube being closed at one end and provided at the other with a flange fastened to said tank head around said opening, and a tube of larger diameter surrounding said first mentioned tube, fastened to it near its flanged end, and provided with perforations near its said fastening, together with a projection from the closed end of said first mentioned tube and a recessed member for engaging said projection mounted on the other 85 head of said tank.

5. In a water heater the combination of a water tight tank having an opening through one wall, and a heater-holding unit inserted through said opening and attached to said wall, the free end of the heater carrying unit 100 engaging a recessed member carried by the adjacent wall of the tank and to be thereby supported.

6. In a water heater a heater-holding unit 105 comprising, in combination, a tube closed at one end, a second tube surrounding the first mentioned one and fastened thereto at one end and a plurality of pins inserted between the free ends of the two tubes to hold said 110 ends concentric one to another.

7. In a water heater the combination of a cylindrical, water-tight tank having an inwardly dished bottom head, and a cylindrical shell for a heat insulating jacket surrounding 115 said tank, the bottom plate of said shell having a series of circumferentially arranged, inwardly curved lugs set on the inner surface thereof having exterior convexly curved faces adapted to engage the interior of the 120 flange of said tank bottom head and center it with reference to said shell when the parts are assembled.

EMIL F. HOLINGER.
